ATTORNEY

UNITED STATES PATENT OFFICE.

WALTER CHMIELARSKI, OF GARY, INDIANA.

FLOATING BATTERY.

1,259,601.

Specification of Letters Patent. Patented Mar. 19, 1918.

Application filed October 15, 1917. Serial No. 196,655.

To all whom it may concern:

Be it known that I, WALTER CHMIELARSKI, (a Russian subject, of Lublin, Poland, who has declared his intention of becoming a citizen of the United States, and has taken out his first citizenship papers,) residing at Gary, in the county of Lake and State of Indiana, have invented a new and Improved Floating Battery, of which the following

10 is a specification.

My invention has for its object to provide a floating battery of large dimensions adapted to carry heavy caliber cannon, rifles, torpedo tubes, anti-air craft guns, etc., for 15 the purpose of warfare and one of the objects of my invention is to provide a structure of the type stated which will sit relatively low in the water and may be painted to correspond with the water coloring and 20 thus rendered largely invisible to approaching vessels.

Another object of the invention is to provide a structure in which the buoyant body is of flat formation so as to present but 25 little edge area to a submarine or to a torpedo.

Again, the invention has for its object to provide a structure of the character stated in which provision is made to render the 30 super-structure bomb-proof.

Still another object of the invention is to provide the structure with stationary fixedly sighted cannon, rifles, or carbines, the muzzles of which are flush with the outer 35 surfaces of the super-structure so as to leave no projections that may be shot away to the damage of the instruments themselves. The invention also makes provision for the location of spy glasses at suitable intervals 40 adjacent to the cannon and rifles so that observers may effectively determine which of the cannon shall be fired in order to hit a determined object.

My invention still further has for its object 45 to provide a floating structure which can be provided with the usual machinery for propulsion and steering so that it may be conveyed from place to place under its own power, although I make no claim, *per se*, to any particular structure of power 50 plant, propelling mechanism or steering mechanism, as such may be of any particular type now well-known in the art.

The invention further has for its object 55 the provision of a large platform space on the floating structure to which captured

aeroplanes may be chained or otherwise fastened.

With other objects in view, the invention also includes those novel details of construction, combination and arrangement of parts, all of which will be first fully described, then be specifically pointed out in the appended claims, reference being had to the accompanying drawings, in which:

60 65

Figure 1 is a perspective view illustrating the invention in use.

Fig. 2 is a top plan view of the invention.

Fig. 3 is a transverse section of the same, parts being removed for convenience of illustration.

70 75

Fig. 4 is an enlarged detail section showing the location of the torpedo tubes and the manner of anchoring the superstructure to the base.

Fig. 5 is a detail view of one of the doorways.

Fig. 6 is a detail section showing the manner of tying the walls of the super-structure together.

80

Fig. 7 is a detail view showing the manner of securing the corner braces.

Fig. 8 is a vertical section showing the manner of tying the platform timbers together.

85

Fig. 9 is a side elevation showing the relative positions of the cannon, the rifles or carbines and the spy glasses for observation.

In the drawings, in which like numerals of reference indicate like parts in all of the figures, 1 represents the platform and 2 the super-structure. In the preferred construction of my invention, the platform 1 is composed of several layers of timber indicated by 3 and 4 in the drawings, 90 the timber layers extending one layer in one direction and the other layer in the opposite direction so that they may be over-lapped and they are tied together by a series of tie bolts 5, at suitable intervals, the bolts 5 being countersunk in the timber and the countersunk bolt holes plugged as at 6, to prevent access of water.

95

In practice, the platform is also edge-faced with steel as at 7, (see Fig. 2) and it 105 is also provided with rings 8 on the top and bottom which are bolted together by a series of bolts 9 and serve to aid in preventing warping of the base and also to aid holding the base laminæ securely together to maintain the base 1 in a single plane. The base 110 may also be provided with a prow 10, for

convenience in transportation through the water.

In practice, the base 1 is designed to be about a quarter of a mile square, while the 5 super-structure 2 will be approximately 200 feet wide by 300 feet long.

The super-structure 2 is built up of an inner shell 11 of steel formed in any suitable way, the corners being secured together, 10 as at 17, (see Fig. 7), it being understood that the shell 11 is built up of steel plates in the usual manner of constructing walls or shells of large dimensions. Surrounding the shell 11 is a wooden wall composed of 15 hard wood layers 12 lap-jointed and cross-jointed to afford the greatest rigidity and strength and around the wall 12 is another steel wall 13 and that wall is surrounded by another wall composed of an inner layer 20 14 of fire-proof paper or pulp, an intermediate layer 15 of brick and an outer layer 14 of fire-proof paper or pulp and around the latter is the outer steel wall 16. The thickness of the various walls may be of any 25 amount desired, although in practice I prefer to make the inner steel shell about five inches thick, the outer steel wall about six inches thick and the intermediate steel shell about three inches thick, the wooden wall 12 30 about thirty inches thick and the brick and paper wall about eighty-nine inches thick although, as before stated, the thickness of the walls may be of any amount found most practical and desirable.

35 The edges of the steel walls are securely braced by the angle irons 17 and are bolted together as at 18—18^a to give a rigid connection.

Suitable doors 19 are provided for entrance 40 into the superstructure from the platform and these doors are also built to conform to the wall structure and are of the "safe-door" type.

The super-structure is also provided with 45 flooring 20—20 to divide the same into a plurality of levels, each level being provided with cannon 21 of long range and high power, the muzzles of which are flush with the outer wall surface of the super-structure. The cannon 21 are arranged in 50 horizontal alinement entirely around the super-structure at intervals, as indicated in Figs. 1 and 8 of the drawings. Above the cannon 21 in horizontal alinement and at 55 corresponding intervals are observation or spy glasses 22, through which the officers in charge may observe the surface of the ocean to determine the approach of a hostile vessel and thus direct the operators of the 60 cannon in firing the same.

Arranged in a horizontal row at frequent intervals above the plane of the spy glasses 22 are powerful rifles, carbines or small light rapid fire guns 23 which may be used 65 in repelling boarding attacks, in the event

that, by any chance, a vessel succeeds in approaching close enough to the structure.

Through the upper wall a plurality of anti-air craft guns 24 are arranged at suitable angles and spy glasses 25 are provided 70 to aid in sighting the anti-air craft guns 24—24.

30 designates torpedo tubes for use in repelling submarine attacks and by making the platform quite shallow, but little opportunity is given for the impact of a torpedo 75 against the same.

Suitable stair-ways 29 are provided for access to the various floors and it is my intention that there be provided hospital wards, 80 sleeping accommodations and all the usual living and hospital facilities of war vessels on the structure but as the same constitute no part of the present invention and may be of the conventional types, I have not deemed 85 it necessary to illustrate the same and furthermore when the battery is to be one that is capable of propelling itself from place to place the usual machinery for propulsion and steering purposes may be located within 90 the super-structure at any convenient place, and as such machinery may be of the usual and conventional type, and, *per se*, is not a part of this invention, I have not deemed it necessary to illustrate the same 95 or describe it.

In order that the super-structure may be securely anchored to the base 1, the super-structure is bolted down by a suitable number of bolts or tie rods 26 and diagonal tie 100 rods or guys 27, as best illustrated in Figs. 3 and 4 of the drawings, it being understood that a sufficient number of tie bolts and guys are employed to firmly anchor the super-structure to the base 1 so that it may withstand 105 the shocks of shells and the cannonading of approaching war ships.

In the use of my invention, a number of the structures are to be launched and cruise slowly around the oceans and attack hostile 110 fleets wherever found. The employment of a large number of high range cannon and arranging them in a series enables attacks from all sides to be made or repelled, it being understood that the cannon of the different floor levels of the super-structure are mounted for fixed elevations and ranges and are of such number as to provide for 115 effective zone firing.

Suitable anchoring cleats or hooks 28 are 120 secured in the base 1 to which captive boats or vessels may be secured and the platform 1 is of sufficiently large area to enable captive air ships to be secured down to the platform and thus conveyed to a suitable 125 base from which the battery came.

From the foregoing description, taken in connection with the accompanying drawings, it is thought the complete construction, operation and advantages of my invention 130

will be readily understood by those skilled in the art.

What I claim is:

1. A floating battery comprising a floating base structure of relatively shallow depth and large surface area, a bomb-proof super-structure mounted wholly on top of the base, the super-structure being relatively of small area to the base, said super-structure inclosing a plurality of floor levels, and a series of cannon mounted on each floor level with their muzzles projecting through the walls of the super-structure and terminating flush with the exterior face of the super-structure, and spy glasses built in the walls of the super-structure for sighting the cannon.

2. A floating battery comprising a floating base structure of relatively shallow depth and large surface area, a bomb-proof super-structure mounted wholly on top of the base, the super-structure being relatively of small area with relation to the base, said super-structure inclosing a plurality of floor levels, a series of cannon mounted on each floor level with their muzzles projecting through the walls of the super-structure and terminating flush with the exterior faces of the super-structure, said cannon being arranged in a horizontal plane in a series at relatively close intervals, and spy glasses built in the walls of the super-structure for sighting the cannon.

3. A floating battery comprising a floating base structure of relatively shallow depth and large surface area, a bomb-proof super-structure mounted wholly on top of the base, the super-structure being relatively of small area with relation to the base, said super-structure inclosing a plurality of floor levels, a series of cannon mounted on each floor level with their muzzles projecting through the walls of the super-structure and terminating flush with the exterior faces of the super-structure, spy glasses built in the walls of the super-structure for sighting the cannon, a series of rapid fire guns also projecting through the walls of the super-structure with their muzzles flush with the outer surface of the same and arranged in a different horizontal plane from that of the cannon and at frequent intervals in series.

4. A floating battery comprising a floating base structure of relatively shallow depth and large surface area, a bomb-proof super-structure mounted on top of the base, the super-structure being relatively of small area with relation to the base, said super-structure inclosing a plurality of floor levels, a series of cannon mounted on each floor level with their muzzles projecting through the walls of the super-structure and terminating flush with the exterior faces of the super-structure, said cannon being arranged

in a horizontal plane in a series at relatively close intervals, spy glasses built into the walls of the super-structure for sighting the cannon, a series of rapid fire guns projecting through the walls of the super-structure with their muzzles flush with the outer surfaces of the same and arranged in a different horizontal plane from that of the cannon and at frequent intervals in series.

5. A floating battery comprising a buoyant flat shallow draft base structure consisting of alternate layers of wood, one layer being cross-lapped with relation to the other, metallic rings bolted to said base on the surfaces of the same and a bomb-proof super-structure firmly secured to the base by hidden tie bolts passing through the super-structure and the base and by diagonal brace rods connecting the sides of the super-structure with the base and provided with tensioning means, one of said metallic rings surrounding the bomb-proof structure so that said structure is located within the space bounded by the ring.

6. A floating battery comprising a buoyant flat shallow draft base structure consisting of alternate layers of wood, one layer being cross-lapped with relation to the other, metallic rings bolted to said base on the surfaces of the same, a bomb-proof super-structure firmly secured to the base within the confines of the inner ring by hidden tie bolts passing through the super-structure and the base and by diagonal brace rods connecting the sides of the super-structure with the base and provided with tensioning means, and a metal facing strip around the edge of the base.

7. In a floating battery, a buoyant base composed of alternate crossed layers of wood, the bottom and top surfaces of said base being parallel and flat, tie bolts passing through the layers of the base, brace rings on the surfaces of the base, tie bolts passing through the rings and base, metallic edge facing strips around the base, a bomb-proof battery structure mounted on the base, said bomb-proof structure comprising a housing formed of an inner steel shell, an intermediate steel shell, an outer steel shell, a wooden wall between the inner and intermediate steel shells and a wall between the intermediate and outer steel shells which is composed of fire-proof material and firing batteries located within the superstructure with their muzzles flush with the outer surfaces of the super-structure, and means for securely anchoring the super-structure to the base.

8. In a floating battery, a buoyant base composed of alternate crossed layers of wood, the bottom and top surfaces of said base being parallel and flat, tie bolts passing through the layers of the base, brace rings on the surfaces of the base, tie bolts passing through the rings and base, metallic edge

115

120

125

130

- strips around the base, a bomb-proof structure mounted on the base within the confines of the inner rings, said bomb-proof structure comprising a housing formed on an inner 5 steel shell, an intermediate steel shell, an outer steel shell, a wooden wall between the inner and intermediate steel shells, and a wall between the intermediate and outer steel shells which is composed of fireproof 10 material, and firing batteries located within the super-structure with their muzzles flush with the outer surfaces of the super-structure, and means for securely anchoring the super-structure to the base.
- 15 9. In a floating battery, a flat buoyant base of relatively shallow depth and large area,
- a bomb-proof super-structure mounted on top of the base, means for securely tying said super-structure to the base, torpedo tubes projecting downwardly through the 20 sides of said super-structure and through said base with their outlet ends flush with the under surfaces of the base, and a plurality of sets of cannon and rifles mounted in the super-structure with their muzzles flush 25 with the outer side and end walls of the super-structure and anti-air craft guns mounted in the top of the super-structure with their muzzles flush with the top wall of the same and means by which the aforesaid 30 ordnance may be sighted.

WALTER CHMIELARSKI.
